US0D1033105S

(12) **United States Design Patent** (10) Patent No.: **US D1,033,105 S**
(45) Date of Patent: ** Jul. 2, 2024

(54) **CHAIR**

(71) Applicant: **SMITH SYSTEM
MANUFACTURING COMPANY,**
Carrollton, TX (US)

(72) Inventors: **Roger John Carr**, Surry (GB); **David Alun Williams**, Ringwood (GB); **Mark McKenna**, East Grand Rapids, MI (US); **Bruce Smith**, East Grand Rapids, MI (US); **Donald Jeffrey Christian**, West Nyack, NY (US); **Randall Joseph Kastalanych**, Plano, TX (US); **Jack Wayne Johnson**, McKinney, TX (US); **John R. Kutzke**, The Colony, TX (US)

(73) Assignee: **SMITH SYSTEM
MANUFACTURING COMPANY,**
Carrollton, TX (US)

(**) Term: **15 Years**

(21) Appl. No.: **29/810,158**

(22) Filed: **Oct. 1, 2021**

(51) LOC (14) Cl. **06-06**

(52) U.S. Cl.
USPC **D6/716**
